CONSTRUCTION FOR STOVES

Daniel P. O'Keefe, Los Angeles, Calif.

Application March 9, 1945, Serial No. 581,889

5 Claims. (Cl. 126—39)

1

This invention has to do with construction for stoves and it is a general object of the present invention to provide a construction for effectively protecting the controls or instruments of a stove against becoming overheated.

Ordinary cooking stoves such as electric stoves or gas stoves commonly used in homes are box-like structures, including one or more cooking compartments and a top burner compartment. The front of such a stove is usually flat or substantially so and is formed primarily by the doors or closures of the cooking compartments and, adjacent the top of the stove, by a panel which is at the front of the burner compartment and which carries the controls and possibly instruments incidental to the stove construction. The doors of the cooking compartments are generally such as to allow some heat to escape and when they are open considerable heat escapes. Any heat escaping from the compartments passes up at the front of the stove and with the usual stove construction heats the operating or control parts or any instruments that may be present in the panel above referred to. It is common in stoves of the general character referred to that a drip tray or trays be provided in the bottom of the burner compartment, such trays ordinarily being accessible through suitable openings provided in the panel that I have referred to.

It is a general object of my present invention to provide heat deflecting means at the panel provided at the front of the stove to occur at the front or fronts of the tray or trays occurring at the panel, so that heat flowing up the front of the stove is deflected away from the controls or instruments provided at the panel.

Another object of my present invention is to provide a stove construction of the general character referred to involving a tray construction which is effective in deflecting heat at the front of the panel through which the tray passes so that heat flowing up at the front of the stove is deflected away from the instruments or control members located at the panel above the tray.

It is another object of my present invention to provide a simple, inexpensive heat deflecting means at the panel of a stove front which does not require any special construction or formation of the panel and which does not materially change or interfere with the appearance or ornamental design of the general stove construction.

The various objects and features of my invention will be fully understood from the following detailed description of typical preferred forms and applications of my invention, throughout

2

which description reference is made to the accompanying drawings, in which:

Fig. 1 is a perspective view of the front or forward end portion of a drip tray for a stove embodying the construction that I have provided by my present invention.

Fig. 2 is a perspective view of the upper portion of a typical console type stove or cooking range incorporating the construction of my present invention.

Fig. 3 is an enlarged detailed sectional view of the construction shown in Figs. 1 and 2, being a view taken as indicated by line 3—3 on Fig. 2 and Fig. 4 is a view similar to Fig. 2 showing a modified form of construction provided by my invention.

My invention can be applied to or incorporated in cooking stoves or ranges generally, and it can be applied most advantageously to stoves of the type ordinarily referred to as the console type, and therefore I have illustrated it applied to that type of stove. The invention can be incorporated in stoves of various designs and of varying types, for instance, it can be employed in oil stoves, electric stoves or ranges, or in gas stoves or ranges.

The stove illustrated in the drawings, being of the console type, is a box-like structure including, generally, a front A, sides B, a top C, and various other elements or parts common to structures of this character. Being of typical console construction the front A is substantially flat and is formed of various parts which are flat and arranged flush with each other. In accordance with common stove construction I have shown the front A formed of two doors 10 and 11 which cover the lower or cooking compartments of the stove and there is a panel 12 arranged across the upper portion of the stove immediately above the doors. In the particular stove illustrated I have shown hinged covers 13 forming the top C and these fit into a recess in the upper edge of the panel 12. It is to be understood that the invention can be applied to a stove wherein the top instead of having hinged covers is plain and has the usual burners exposed, ready for immediate use.

In the stove illustrated there are two lower or cooking compartments and for purpose of example one of these may be considered an oven and the other a broiler. It is to be understood that the invention can be applied to a stove involving a single cooking compartment which may be either a broiler or an oven or a compartment for any other cooking or heating purpose.

In the drawings the cooking compartment cov-

ered by the door 11 is designated by numeral 13^a and may be considered either a broiler compartment or an oven.

Immediately above the cooking compartments there is an upper or burner compartment 16, the front of which is covered by the panel 12. The compartment 16 accommodates the usual burners (not shown) and may be shaped and proportioned to accommodate the necessary structural elements incidental to the burners. It is to be understood that the interior of the stove can be divided into various desired compartments through suitable partitions. In the drawings, a partition 17 is shown separating the cooking compartment 13^a from the upper or burner compartment 16.

In accordance with common stove construction a gas manifold 18 extends across the front of the stove through the forward portion of the compartment 16, and suitable gas valves or cocks 19 are supplied from the manifold and deliver gas to mixing devices 20 which supply the necessary mixture of gas and air to the burners located in the compartment 16. In accordance with common stove construction the stems 21 of the cocks 19 project through the panel 12 and carry operating members or knobs 22. The operating knobs 22, being thus located at the front of the panel 12, which is located at the upper portion of the front of the stove, are conveniently accessible for operation. The panel 12 is flat or substantially so and is vertically disposed to be flush or substantially flush with the fronts of the doors. In addition to the operating knobs other control elements such as heat control means, or the like, 35 may be provided at the front of the panel 12. When I refer to a control element or controls I mean to include not only knobs for operating gas cocks or for operating electrical controls, but any other control member or members or instruments which may be required or desired in a construction of the character under consideration.

In accordance with my invention I provide a baffle or heat deflector at the front of the stove between the controls at the panel and the lower cooking compartments and I make such deflector in the form of a projection projecting forward from the front face of the panel 12, which face is generally a flat vertical face.

In the preferred form of my present invention I make the heat deflector a part of the drip tray or trays provided in the burner compartment of the stove.

In the drawings I have shown a typical stove construction wherein drip trays 50 are slidably supported in the lower portion of the burner compartment 16 to be operable into and out of position in that compartment through openings 80 provided in the lower portion of the panel 12. In the particular forms of the invention illustrated there are two trays 50. In Fig. 2 I show an arrangement wherein the two trays together extend across substantially the entire width of the stove front whereas in Fig. 4 I show an arrangement wherein the trays are narrower and are spaced a substantial distance apart requiring a supplemental deflector construction that I will hereinafter describe.

The trays 50 in accordance with common stove construction are shallow sheet metal elements supported through suitable construction in the stove to slide horizontally into position through the openings 80. In accordance with the usual tray construction the forward or front wall 81 of each tray occurs at or close to the front of

the panel 12 when the tray is in position in the stove, and an ornamental cover plate 82 is carried by the front wall of the tray to overhang and conceal the tray opening 80 in the panel 12. In the construction illustrated the plate 82 is secured to the wall 81 by screws 51.

In accordance with my present invention the tray or trays of the stove, as above described, are provided with forwardly projecting deflectors 32. Where there are two trays, as shown in Fig. 2 of the drawings, the deflectors 32 extend continuously across the front of the trays and where the trays have front plates 82 such as I have described the deflectors project forward from those plates a substantial distance or to a point well forward of the controls at the front of the panel, as I have clearly shown in Fig. 3 of the drawings.

In accordance with the preferred construction the deflectors are integral extensions or projections on the plates 82 or on the fronts of the trays and the lower sides of the deflectors are curved, as at 56, so that heat striking them as it flows up at the front of the stove is deflected up and out, as indicated by the arrows in Fig. 3. The tops or upper sides of the deflectors can be of any desired configuration, that is, they can be plain flat surfaces or they can be provided with suitable recesses or depressions 99 to form finger grips to facilitate grasping by the fingers of the operators so that the deflectors not only serve as heat deflectors but also as convenient handles by which the trays can be operated.

In the case of the construction shown in Fig. 2, where the two trays 50 extend substantially across the entire front of the stove, there is but a small gap between the deflectors on the front of the trays, making it unnecessary to supplement the deflectors of the trays by any other construction.

In the form of the invention shown in Fig. 4 the trays are far enough apart and there are controls or parts at the panel above the gap between the deflectors of the trays, making it 45 advantageous to provide supplemental deflecting means between the trays. In that case it is advantageous to provide a fixed or permanent deflector 32^a on the front of the panel 12 to be in line with the deflectors of the trays and to effectively fill the space or gap between the deflectors of the trays so that practically all of the heat flowing up at the front of the stove is deflected away from the panel where the controls are located. The deflector 32^a may be like the 55 deflectors 32 in shape, design and proportioning, or like the deflectors 32 and the plates 82, so that the supplemental deflector together with the deflectors of the trays form a uniform, slightly structure across the front of the stove, as shown 60 in Fig. 4 of the drawings.

By my present invention I have provided a stove construction by which the controls at the panel are effectively protected against overheating without the necessity of providing any special 65 formation or construction for the panel itself. I accomplish effective heat deflection by simply providing the deflectors on the front of the trays and since the trays are parts that can be very easily removed or interchanged 70 I can, in practice, supply various stoves with deflectors of various shapes, designs, or appearances and thus effectively vary the stove design without appreciable change in construction. It is also to be noted that the deflectors not only 75 effectively deflect the heat while the stove is in

use, but that they provide convenient readily accessible handles for the trays, by which the trays can be operated when it is desired to remove them for cleaning or other purposes.

Having described only typical preferred forms and applications of my invention, I do not wish to be limited or restricted to the specific details herein set forth, but wish to reserve to myself any variations or modifications that may appear to those skilled in the art and fall within the scope of the following claims:

Having described my invention, I claim:

1. A stove including a cooking compartment, a door at the front of the stove closing the compartment, a panel at the front of the stove above the door and having an opening, a plurality of control elements at the front of the panel, a tray operable through the opening in the panel, a heat deflector carried by the tray normally projecting forward from the panel and forward beyond the front of one of the control elements and located between the door and one of said elements, and a fixed heat deflector adjacent to and in alignment with said first deflector projecting forward from the front of the panel and forward beyond the front of another of said elements, said deflectors being immediately adjacent the door and the panel and together deflecting heat away from all of said elements.

2. A stove including a cooking compartment, a door at the front of the stove closing the compartment, a panel at the front of the stove above the door and having an opening, a plurality of control elements at the front of the panel, a tray slidable through the opening and normally located in the stove behind the panel, a heat deflector carried by the front of the tray to normally project forward from the panel between the door and one of said elements to a point forward of said element, and a fixed heat deflector projecting from the front of the panel below another of said elements to a point forward of said other element, the deflectors being elongate members arranged horizontally and in substantially end to end relationship at the front of the panel immediately adjacent the panel and door and together deflecting heat from all of said elements.

3. A stove including a cooking compartment, a door at the front of the stove closing the compartment, a panel at the front of the stove above the door and having a tray opening therein, a control element at the front of the panel, a tray engaged through the opening and supported in the stove behind the panel, a heat deflector supported by the tray and normally projecting forward from the panel, and forward beyond the control element and located between the door and said element, the deflector being immediately adjacent the door and panel and the lower side of the deflector being curved to extend upwardly and outwardly, and means stopping the tray fully engaged in the stove and supporting the deflector in operating position relative to the control element including a cover plate fixed on the tray

and normally engaging the front of the panel above and below the opening to completely close the opening.

4. A stove including a cooking compartment, a door at the front of the stove closing the compartment, a panel at the front of the stove above the door and having an opening, a plurality of control elements at the front of the panel, a tray slidable through the opening and normally located in the stove behind the panel, a heat deflector carried by the front of the tray to normally project forward from the panel and forward beyond the control elements between the door and one of said elements, and a fixed heat deflector projecting from the front of the panel and forward beyond the control elements below another of said elements, the deflectors being elongate members immediately adjacent the door and panel and arranged horizontally and in substantially end to end relationship at the front of the panel, the lower sides of the deflectors being curved and the deflectors together deflecting heat from all of said elements.

5. A stove including a cooking compartment, a door at the front of the stove closing the compartment, a panel at the front of the stove above the door and having an opening, a plurality of control elements at the front of the panel, a tray slidable through the opening and normally located in the stove behind the panel, a plate carried by the front of the tray to cover the opening in the panel, a heat deflector carried by the plate to normally project forward from the panel and forward beyond the control elements between the door and one of said elements, and a fixed heat deflector projecting from the front of the panel and forward beyond the control elements below another of said elements, the deflectors being elongated members located immediately adjacent the door and panel and arranged horizontally and in substantially end to end relationship at the front of the panel to deflect heat from all of said elements.
